United States Patent Office.

CHARLES LYNE, OF PHILADELPHIA, PENNSYLVANIA.

Design No. 3,159, dated August 11, 1868.

DESIGN FOR PERAMBULATOR-BODY.

The Schedule referred to in these Letters Patent and making part of the same.

TO ALL WHOM IT MAY CONCERN:

Be it known that I, CHARLES LYNE, of Padstow, county of Cornwall, England, residing in the city of Philadelphia, county of Philadelphia, and State of Pennsylvania, have originated a Design for "Perambulator-Body," of which the following is a full, clear, and exact description, reference being had to the accompanying drawings, making part of this specification.

My perambulator-body is made in the form as shown in the drawing, and is constructed of wood, and gracefully rounded on the back. From the point A to the point B there is a slight inclination of about ten degrees. From point A the body curves downward until it reaches point C, where it gradually extends forward to point D; it then curves downward and extends out, and thence curves up to the point E, which forms the front or foot-rest.

The under side of the body, from the point B to the point F, is cut out in the shape of a scroll, and forms the seat, and from point F there is a gradual curve extending forward and up to the point E.

Having thus described my invention, what I claim, and desire to secure by Letters Patent, is—
The design for perambulator-body herein set forth and shown.

Witnesses:

ISAAC R. OAKFORD,
HENRY ROELLIG.

CHARLES LYNE.
